US00D786300S

(12) **United States Design Patent** (10) Patent No.: **US D786,300 S**
Hashmi et al. (45) Date of Patent: ** May 9, 2017

(54) **DISPLAY SCREEN OR PORTION THEREOF
WITH A GRAPHICAL USER INTERFACE**

(71) Applicants: **Ghazala Hashmi**, Holmdel, NJ (US); **Richard Klemm**, Basking Ridge, NJ (US); **Michael Seul**, Basking Ridge, NJ (US)

(72) Inventors: **Ghazala Hashmi**, Holmdel, NJ (US); **Richard Klemm**, Basking Ridge, NJ (US); **Michael Seul**, Basking Ridge, NJ (US)

(73) Assignee: **BIOINVENTORS & ENTREPRENEURS NETWORK LLC**, Warren, NJ (US)

(**) Term: **15 Years**

(21) Appl. No.: **29/584,586**

(22) Filed: **Nov. 16, 2016**
